UNITED STATES PATENT OFFICE.

JOSEPH WEIS, OF PORT CLINTON, OHIO.

SUSPENDERS.

No. 928,722.

Specification of Letters Patent.

Patented July 20, 1909.

Application filed May 22, 1908. Serial No. 484,387.

To all whom it may concern:

Be it known that I, JOSEPH WEIS, a citizen of the United States, residing at Port Clinton, in the county of Ottawa and State of Ohio, have invented certain new and useful Improvements in Suspenders, of which the following is a specification, reference being had therein to the accompanying drawing.

10 This invention relates particularly to the tabs of suspenders. Provision is made for tabs to connect with the trousers and tabs to connect with the drawers.

15 The invention contemplates a novel formation of tabs for this purpose; and it has in view a supporter especially adapted for wear by stout or corpulent persons.

20 When read in connection with the description herein, the details of the invention will be apparent from the accompanying drawings, forming part hereof, wherein an embodiment of the invention is disclosed, for purposes of illustration.

25 Like reference-characters refer to corresponding parts in the several views of the drawings, of which—

30 Figure 1 is a view of the outside of the front or side tabs; Fig. 2 is a view of the inner side thereof; and Fig. 3 is a side view thereof.

35 Referring more particularly to the drawings, 7 designates a loop at each front end of the main strap of the suspenders. One end of the loop is secured by a detachable fastener 8, or in any other suitable manner, so that the loop can be readily opened. At the bend of the loop is an opening 9.

40 Depending from loop 7 are outer tabs 10 and 11, for connection with the trousers, and an intermediate tab 12, for connection with the drawers. Tabs 10 and 11 each consist of a buttonhole portion 13 and a

sustaining portion 14, the latter portion of each of these tabs being passed through the fold of loop 7 and down through the opening 45 9, below which opening they meet and are joined to form tab 12. The sustaining portion of one of tabs 10 and 11, for instance that of tab 10, is extended downwardly below opening 9 farther than the sustaining 50 portion of the other and a buttonhole piece 15 is formed on this end. The material of the sustaining portion of tab 11 is sewed or otherwise suitably secured to that of tab 10 above the buttonhole of buttonhole piece 15. 55 By this arrangement the strain between the trousers and the drawers is equalized.

Having thus described my invention, what I claim as new, and desire to secure by Letters Patent, is—

60 1. Suspenders having a loop with an opening therein, and a tab passed from each side into the loop and down through the opening, the outer ends of the tabs having means for attachment to a garment, and the inner end 65 of one of the tabs having means for attachment to a garment and having the inner end of the other tab attached thereto.

2. Suspenders having a loop with an opening therein, and a tab passed from each side 70 into the loop and down through the opening, the outer ends of the tabs having means thereon for attachment to a garment, one of the tabs being extended downwardly below the opening farther than the other tab 75 and having on its end means for attachment to a garment, and the other tab being attached thereto.

In testimony whereof I affix my signature in presence of two witnesses.

JOSEPH WEIS.
